UNITED STATES PATENT OFFICE

115,577

DESIGN FOR A BUILDING

Orville H. Sowl, Ord, Nebr.

Application April 25, 1938, Serial No. 76,748

Term of patent 7 years

To all whom it may concern:

Be it known that I, Orville H. Sowl, a citizen of the United States of America, residing at Ord, in the county of Valley and State of Nebraska, have invented a new, original, and ornamental Design for Buildings, of which the following is a specification, reference being had to the accompanying drawings, wherein:

Figure 1 is a top plan view of a building, showing my new design.

Figure 2 is a view in front elevation thereof.
Figure 3 is a central vertical sectional view taken on the line 3—3 of Figure 2.

Figure 4 is a horizontal sectional view taken on the line 4—4 of Figure 2.

I claim:

The ornamental design for a building, as shown.

ORVILLE H. SOWL
